UNITED STATES PATENT OFFICE.

WILLIAM J. COPP, OF HAMILTON, CANADA.

DESIGN FOR A HALL-STOVE.

SPECIFICATION forming part of Design No. 21,345, dated February 16, 1892.

Application filed December 30, 1891. Serial No. 416,607. Term of patent 3½ years.

To all whom it may concern:

Be it known that I, WILLIAM J. COPP, a citizen of Canada, residing at Hamilton, in the county of Wentworth, in the Province of 5 Ontario, Canada, have invented and produced a new and original Design for a Hall-Stove, of which the following is a specification, reference being had to the accompanying drawing, forming part thereof.

10 The design-drawing represents a perspective view of a hall-stove, showing the front, side, and top, with the top partially open, this view being deemed sufficient to fully illustrate my design.

15 My design consists of a hall-stove in box form elaborately designed and ornamented, as fully shown and set forth in the accompanying drawing.

In the design-drawing the box-stove is indicated by the letter A, and its legs by B.

C represents the ornamental design on the side of the stove, while the door at the front

of the stove, also ornamented, is indicated by D, and the damper by E. The contour of the stove is heightened in effect by the projecting design of the upper part, as indicated by F. 25

H is the top, and having handle J and lifting-plate K, the pattern and ornamental design of the scroll-work being fully illustrated in the accompanying drawing. 30

I claim—

The design for a hall-stove, as herein shown and described, the same consisting of the box or body of the stove A, elaborately ornamented and designed, as at C and F, the legs B, and the front door D, ornamented, as shown, together with the top H, with its front projecting handle J, all formed, arranged, and designed as fully shown in the accompanying drawing. 35

WILLIAM J. COPP.
